BOTTLE CAPPING MACHINE

Linus E. Greene, Fitchburg, Mass., assignor to
 Cowdrey Products Company, Inc., Fitchburg,
 Mass., a corporation of Massachusetts

Application August 12, 1936, Serial No. 95,655

19 Claims. (Cl. 226—86)

This invention relates to automatic machines for capping bottles and like containers, having for its object to provide a construction simple in part and more efficient in operation than those heretofore proposed.

5 With these and other objects in view the invention resides in the novel details of construction and combinations of parts as will be disclosed more fully hereinafter and particularly pointed out in the claims.

10 Referring to the accompanying drawings forming a part of this specification and in which like numerals designate like parts in all the views—

Fig. 1 is a side elevation of the entire machine;

15 Fig. 2 is a front elevation of the machine;

Fig. 3 is a top plan view of the machine with a part of the cover broken away to illustrate more clearly some of the mechanism controlling the cap feeding and cap applying apparatus;

20 Fig. 4 is a horizontal sectional view through the head of the machine taken as on the line 4—4 of Fig. 6 and looking in the direction of the arrows;

Fig. 5 is a detail horizontal plan view illustrating the feeding of a cap to capping position over a bottle;

25 Fig. 6 is a vertical sectional view taken as on the line 6—6 of Fig. 2 and looking in the direction of the arrows;

Fig. 7 is a vertical sectional view taken as on the line 7—7 of Fig. 2 and looking in the direction of the arrows;

30 Fig. 7a is an enlarged detail view of the bent rocker and its control spring;

Fig. 8 is a vertical sectional view through one of the cappers and illustrating mechanism associated therewith;

35 Fig. 9 is a vertical sectional detail of the lower end of one of the cap magazines;

Fig. 10 is a horizontal sectional view through the lower end of a cap magazine; and

40 Fig. 11 is a vertical sectional detail illustrating how the bottommost cap, in the stack of caps in the magazine, is deposited and the stack of caps thereabove retained within the magazine until another cap is needed.

45 This machine comprises a base portion generally indicated by the numeral 1 the legs of which are provided with nut and screw means such as shown at 2 for levelling the machine on the floor. This base portion has a flat top secured to which is a long vertical bearing member 3 to the bottom of which is fixed a casting 4 carrying two miter gears 5 and 6, the miter gear 5 being attached to the lower end of a long worm 7 extending upwardly and threaded through a nut

8 rigidly carried at the lowermost end of a tubular pillar 9 slideable in the bearing 3 and bolted or otherwise firmly secured as at 10 to the underside of the capping head generally indicated by the numeral 11. The other miter gear 6 is attached to one end of a horizontally extending shaft 12 to the front end of which is fixed the hand wheel 13 by means of the rotation of which the capping head may be raised or lowered with respect to the base 1 of the machine to accommodate bottles or containers of different heights. In order to lengthen the bearing 3 it may be found desirable to secure a tubular sleeve 14 above the top of the base 1.

5 A liner 20 is carried on the top of the base 1 and receives therethrough the lower squared end of a shaft 21 extending downwardly from the capping head, and disposed on the squared portion of this shaft is one end of a bent lever 23 the other end of which is pinned as at 24 to one end 20 of an adjustable link 25, the other end of said link being pinned as at 26 to a rod 27 provided with a horizontal hole therethrough in which is fitted a removable pin 28 adapted to engage one of a plurality of holes 29 formed in a depending 25 portion of a yoke 30 of substantially U-shape or channel form, the upstanding sides of this yoke having rigidly fixed thereto the two slides 31 and 32 disposed in a horizontal plane on opposite sides of the line of bottle travel, as best seen in Fig. 1, 30 and to these slides are secured spring pawls such as indicated at 33.

These pawls are of any well known formation each carrying a horizontal arm 34 extending normally in a direction transverse to the length of 35 said slides and are for the purpose of engaging a bottle and sliding said bottle over the base 1 of the machine into bottle capping position as the slides are actuated. It will be understood that the bottles are filled before they reach the 40 capping machine and that these slides and pawls will move the filled bottles step by step until they reach the capping position, said pawls in their inoperative movement with respect to the bottles capable of having their arms pivotally yield 45 against spring tension to slip past a bottle into operative position therebehind so that, upon the next operative stroke of the slides and pawls, that bottle will be moved toward capping position. This bottle moving mechanism is well known in 50 the art and therefore requires no further explanation. The link 25 is made adjustable, and the plurality of holes 29 are provided in the yoke, to enable the pin 28 to be engaged in one of said holes to control the step by step movement of the 55

bottles as may be necessary when bottles of different diameters are to be capped by this machine, and the pawls 33 may be adjustably secured to their slides in accordance with the size of the bottles, all as will be readily understood.

In the capping head there is a motor 40 with a built-in speed reducer generally indicated by the numeral 41 directly connected to rotate a drum-shaped cam member generally indicated by the numeral 42 all mounted in suitable bearings, said member having a cam groove 43 formed in its cylindrical surface and a second cam groove 44 formed in its vertical flat face. Running in the cam groove 43 is a roller 45 mounted on one end of a lever 46 the other end of which is securely pinned to the upper end of the vertical shaft 21 extending downwardly from the capping head and having the lower end of square formation as heretofore described. Therefore it will be understood that the cam groove 43 causes oscillation or rocking, through the lever 46, of the shaft 21, and this in turn oscillates the bent lever 23 to reciprocate the slides 31 and 32 carrying the bottle moving pawls 33 (see Figs. 1, 2, 4 and 7). The other cam groove 44 has running therein a roller 47 carried intermediate the ends of a lever 48 extending from front to rear of the capping head, the rear end of said lever being pivoted as at 49 to the top of an eyed rod 50 held in vertical position by the guide lugs 51 and 52 formed integrally with the capping head. This rod has a collar 53 pinned thereto just under the upper lug 51, and between this collar and the floor of the capping head there is disposed a coiled spring 54 surrounding the rod, thereby normally establishing a tension sufficient to force upwardly the pivoted end 48 of the lever 48. The forward end of this lever is pivoted to one end of a link 55, the other end of which is pivotally connected as at 56 to the top of the capper carrier generally indicated by the numeral 57. Thus it will be understood that the cam groove 44 causes vertical movement of the forward end of the lever 48 thereby giving vertical reciprocations to the capper carrier. Due to the fact that bottles of like size vary slightly in height and the action of the cam groove 44, governing the vertical reciprocations of the capper carrier, is positive, and further that it is necessary that the height of the bottles govern the position of the capper at the lower end of its stroke, it is necessary that provision be made for permitting a yielding of the lever 48 to allow the roller 47 to remain in said groove. This is accomplished by the spring 54 which permits a downward yielding of the rod 50. In other words, if a bottle is high and the end of the lever which is attached to the capper carrier reaches the end of its stroke before the roller 47 has reached the limit of its throw, the rear end of said lever may be depressed or yield against the tension of the spring 54.

In the capper carrier are two holders 60 and 61 made to receive vertical tubular magazines 62 and 63 for the caps, said holders so formed that the tubular magazines may enter the top portion thereof but are restrained from passing entirely therethrough, such for example as by providing the internal shoulder indicated at 64 in Fig. 9 against which the bottom of a magazine may rest. The magazine may be made of glass so that the caps may be visible, or a window device such as indicated at 65 may be provided in the wall of the holder, so it may be known when the stack of caps in the magazine needs replenishing. The caps in the magazine are free to move downward-

ly therein by gravity to the bottom thereof, it being understood that the caps are nested in a magazine stack as indicated in Fig. 9, each cap being preformed with a downwardly extending skirt portion containing a plurality of partially folded pleats.

Each holder such as 60 at its lower end is provided with a plurality of spaced and pivoted cap supporting dogs, three being shown in the drawings. In other words and with particular reference to Figs. 4, 5, 9, 10 and 11 it will be seen that each dog such as 66 is centrally pivoted exteriorly of the magazine holder, the upper end of each dog being outwardly pressed from the holder by virtue of a spring 67, thereby forcing inwardly the lower end of the dog. A roller 68 is freely supported at the lowermost end of the dog and just thereabove there is provided an inwardly directed toe 69 of such extent that when the dog is moved outwardly by the spring 67, the toe will 20 extend inwardly of the magazine to lie under the edge of the lowermost cap such as 76 and support the entire stack of caps in the magazine, but when the dog is oscillated about its pivot said toe will move outwardly with respect to the magazine and permit the stack of caps to drop.

As the capper carrier nears the bottom of its down stroke the small roller 68 on a dog will contact with a cam surface 71 of the three-arm cam piece 72, each arm having a similar cam surface 30 for engagement with the rollers of the other similarly formed dogs. These rollers contact the cam surfaces through holes such as 73 formed in the cap receiving plate such as 74 to the underside of which the cam piece is attached. Continued 35 downward movement of the magazine therefore causes the rollers to ride over the cam surfaces and oscillate the dogs, causing the toes to move outwardly from under the lowermost cap in the stack and permit the stack to fall under the urge 40 of gravity until the lowermost cap rests upon the upper surface of the cap receiving plate 74 as seen in Fig. 11. This happens at the end of the down stroke of the magazine, and when the capper carrier starts its top stroke the magazine will move 45 therewith, and the rollers 68 will ride upwardly over the cam surfaces so that the springs 67 will oscillate the dogs to bring the toes thereof inwardly of the magazine to a position beneath the edge of the skirt of cap 75 in the stack next above 50 the lowermost cap 76, and continued upward movement of the magazine causes the entire stack of caps to be carried therewith, with the cap 75 then becoming the lowermost cap in the stack, since the cap 76 has been left deposited on the 55 plate 74 ready for lateral movement into cap applying position on the bottle in a manner which will be described later.

The cam groove 44 also has running therein a roller 80 carried at one end of a bell crank lever 60 81 pivoted as at 82 the other end of said lever being pivotally connected as at 83 to one end of an adjustable link 84 the other end of which is connected to a lug 85 extending upwardly at the rear end of a horizontally reciprocable slide 86 65 working in the guides such as 87 on the floor of the capping head. The forward end of this slide has an upstanding pin secured thereto upon which are mounted for free rotation a pair of rollers 88 and 89, one roller above the other, and held in contact with these rollers by the spring 90 is a pair of crossed arms 91 and 92, likewise one above the other, and pivoted respectively as at 93 and 94 at their rear ends to the capping head base on opposite sides of the slide 86. See 75

Figs. 4 to 7 inclusive. Each arm carries, substantially midway its length and depending downwardly therefrom, a pin such as 95 normally resting behind the latch 96 upstanding from one end 5 of the bent rocker 97 pivoted as at 98 to the capping head base as clearly illustrated in the left hand side of Fig. 5. Stop pins 99 and 100 are provided for the bent rocker 97 to limit the oscillatory swing thereof, and a spring 101 is coiled 10 about a pointed rod yieldably held in a pivotally mounted stud, the axis of said rod substantially bisecting the angle formed by the arms of said rocker, the pointed end of said rod seated in a recess at the approximate median point of the 15 rocker, whereby said spring pressed rod is capable of holding the bent rocker against the stop pins in either extreme of rocker movement by reason of the fact that the line of pressure of the spring passes from side to side of the rocker 20 pivot 98 during movement of the rocker. A bar 102 carried by the slide 86 is adapted to contact one end of the bent rocker in the forward movement of the slide and move said rocker up against the stop pin 100 in which position the latch lug 25 96 carried by the rocker will be in position to engage the pin 95 and hold the cross arm 91 in the position shown in Fig. 5.

Thus it will be understood that, upon the rearward movement of slide 86, the rollers 88 and 89 30 carried at the front end thereof will cause the crossed arms 91 and 92 to be oscillated about their pivots against the tension of the spring 99 interconnecting the rear ends of said arms, and when this occurs the pin such as 95 carried by 35 each of said arms will travel in an arcuate path, ultimately striking and riding over the inclined vertical surface of the lug latch such as 96 formed on each of the similar and bent rockers such as 97, in this movement said pin oscillating its associated bent rocker about its pivot and ultimately 40 coming to rest behind the lug latch thereof where said pin is retained until released in a manner to be described later. Here it might properly be stated that two similar crossed arms are used, as 45 well as two similar cap magazines, and two similar cap applying devices, because two bottles or containers are intended to be capped simultaneously by this machine, there being employed a second bent rocker 103 which is a duplicate of 50 the rocker 97 but oppositely mounted with respect thereto on the other side of the slide 86 and cooperatively associated with the arm 92 all as will be clear from the drawings.

From what has just been described it will 55 therefore be understood that a cap deposited from the magazine on the plate 14 may be slid by one of these crossed arms from a position beneath the magazine to a point on the platen 104 under a capper device ready for application to a bottle, 60 said platen held by the pair of rods 105 and springs 106 to the capper carrier 57. There are two capping devices of similar construction, placed side by side, and generally indicated in Fig. 2 by the numerals 110 and 111, having identical 65 operation and therefore in the following a description of only one of these devices will be given because of the numerous parts in each device.

With particular reference to Fig. 8 the capper 70 generally identified by the numeral 111 comprises a casing 112 which is hollow and cylindrical, and a cap 113 which is telescopically connected with the casing and mounted outside it. This cap is integrally attached to the capper 75 carrier 57 and hence is operated coincidentally

therewith. The bottom of the casing 112 has an opening 114 which is provided with teeth (not shown for clearness) slanting and having the same general shape as the flutes or pleats on the caps contained in the magazine, so that when the 5 capper descends and a cap is engaged in the opening 114, the teeth or conformations of said opening will register with the pleats of the cap, or if accurate registration does not exist, the conformations and shape of said opening will 10 cause a circular movement of the light weight paper cap to bring the teeth or conformations and pleats into registry.

As previously stated the cap deposited from the magazine will have been brought by a crossed 15 arm such as 92 over into bottle applying position over the aperture such as 115 formed in the platen 104 so that when a bottle is below said aperture the cap will be in position for application to the bottle. In other words, as the cap 20 carrier 57 descends a plunger 116, in the form of a circular plate attached to the bottom of a rod 117, is pressed by the spring 118 so as to hold the paper cap 119 against the top of the bottle 25 120, the spring 118 permitting however a yielding of the plunger as the casing 112 still further descends. This rod has a cross pin 121 which operates in a pair of vertical slots 122 in a hollow cylinder 123. A partition 124 is fixed to the casing 112 and on this partition are pivoted as at 125 30 a circular series of levers 126 having forming surfaces 127.

As the casing 112 descends still further, rollers 128 on said levers will engage a conical cam 129 fixedly mounted with respect to a cylinder 35 130 formed as a central inward extension of the cap 113. Downward movement of this cam oscillates these levers so that their lower ends are moved inwardly and the surfaces 127 come into contact with the peaks of the pleats on the bottle 40 cap to press them down into a position to fix the bottle cap tightly on the bottle. Between the two cylinders 123 and 130 is a coil spring 131 which tends to force the cylinder 123 downwardly 45 so that the plunger 116 will be in position to hold the cap against the upper end of the bottle before the pivoted levers begin their operation of crimping the cap tightly about the neck of the bottle. The platen 104 is adapted through the rods 105 and springs 106 to yield downwardly 50 coming into the position shown in Fig. 8 at the end of the down stroke of the capper carrier so that the final securement of the cap to the bottle may be made above the plane of said platen. A garter spring 132 passes around the levers 126 to 55 hold the rollers 128 against the cam 129. The construction and operation of this capper is substantially the same as that disclosed in an application for U. S. Letters Patent by Arthur C. Gough filed June 22, 1935 under the Serial No. 27,995 60 entitled Bottle capper.

When a bottle is beneath either capper, and the capper is forced down over the bottle to apply a cap, the rod 140 is held back from part of the stroke and its relative position in the 65 capper carrier is changed. In other words, the capper device has an upstanding lug 141 at the top thereof to which is pivoted a rocker arm 142, one end of the arm pivoted to the upper extremity of the rod 140, the lower end of said 70 rod having a pin and slot connection as indicated at 143 with the cylinder 123 previously described, the spring 131 normally tending to separate the members 123 and 140, but upon downward movement of the capping device the presence of a 75

bottle being capped will cause the plunger to move upwardly within the capper casing 112 so that upon still further downward movement of the capper device and the telescoping of the parts 112 and 113, the pin and slot connection 143 will ultimately be such that the rod 140 will move relatively upwardly out of the capper device thereby rocking the arm 142. The other end of this arm is pivotally connected to a link 144 attached to one end of a bell crank lever 145 pivoted as at 146 to a part of the capper carrier 57, the other end of the lever being ball shaped as indicated at 147. The position of this bell crank lever is such that when the capper carrier is in its lowermost position and the rod 140 has had the relative movement just described, the ball end 147 of said lever will have been moved to the right as seen in Fig. 8 against the bent rocker 97 oscillating the latter and releasing the pin 95 from behind the latch 96 to free the crossed arm 91 from its position shown in Fig. 5. When this is done the spring 86 will cause said arm 91 to be free to move the deposited cap from its position at 148 to the capping position shown at 149. However, it is to be particularly observed that this unlatching of the arm 91 takes place only through the oscillation of the bell crank 145 and said crank is only oscillated by virtue of movement of the rod 140 out of the upper end of the capper; in other words, when this relative movement does not take place, the ball end 147 of the bell crank 145 will remain in a dependent vertical position as indicated in Fig. 6.

Stated in other words and with particular reference to Fig. 5 there is shown on the left a view of the cap positioning crossed arm 91 in the position occupied at the time when, on the previous stroke, a bottle was under the right hand capper (aperture 115 in platen 104) and received a cap. There was however, no bottle under the left hand capper wherefore the cap, furnished the left hand capper during the previous cycle, may be seen in position at 149 on platen 104 where it will remain and move up and down with the platen until such time as it is placed on a bottle. Its placement and securement on a bottle will, as above described, cause the relative movement mentioned in connection with the rod 140, and this in turn will throw the bell crank 145 to unlatch the cap positioning arm 91 by movement of the bent rocker 97 to cause it to assume an equivalent position to the bent rocker 103 shown in Fig. 5. The arm 91 thereupon will follow its roller 88 during the next forward movement of the slide 86 and in this movement will shove the cap shown at 148 to the position shown at 149 under the capper ready to be applied to the next bottle, Fig. 5 showing in its right hand half a similar movement being performed by the other cap positioning arm 92.

Hereinbefore it was stated that the spring 101 was capable of holding the bent rocker 97 against either of its stop pins 99 and 100 at the limit of movement of the rocker in either direction. While this is true the following explanation should however be made. In Fig. 5 the bar 102 is shown advancing with the slide 86 in the direction of the arrow, and making contact with one arm of the bent rocker 103. Continued forward motion of the slide will cause said bar to tilt the rocker until it comes to rest against the stop pin 100. On the next backward movement of the slide the pin 101, projecting downward from the cap positioning arm 92 will strike and

ride over the oblique cam surface of the latch piece 102 on said rocker, moving the rocker slightly away from said stop pin 100 until the pin 101 has passed by said latch piece. This movement of the bent rocker is not enough so that the line of pressure of the spring 103 has passed by the pivot center of the rocker, wherefore the pressure of said spring will return said rocker to said stop pin 100. It is only movement of the rocker as by the ball end of a bell crank such as 145 that the rocker 103 will be moved sufficiently to flop over against its other stop pin 101 and remain there under pressure of its spring.

From the foregoing description it will therefore be understood that the pawls 33 feed the filled bottles in step-by-step manner the distance of two bottles at each step, so that two bottles can be capped simultaneously. Also that the cap magazines 60, 61 and the capping devices 110, 111 are integrally joined together to move in unison as a cap carrier 57, and when the cap carrier moves upwardly single caps are slid from positions below the magazines into positions under the cappers by the crossed arms 91, 92 working under tension against the superposed rollers 86, 88 carried by the slide 86, and that when the cap carrier moves downwardly said caps are applied to the bottles while at the same time the lowermost cap in each magazine is being deposited on the cap receiving plate such as 74 to 30 be laterally slid to capping position upon the next upward movement of the cap carrier, thereby completing a cycle which is repeated so long as the drum cam 42 is rotated. The slide is reciprocated in time with the reciprocations of the cap carrier, the slide moving forwardly during the raising of the cap carrier and moving rearwardly during the lowering of said cap carrier, with the crossed arms having their cap engaging ends moved in a direction toward the magazines by the rearward movement of the slide, and said ends moved in a direction toward the cappers by the forward movement of said slide. This is all controlled by the cam whose grooves 43, 44 are so formed that one complete revolution of the cam causes a complete cycle of the above recited operating mechanisms.

It is obvious that those skilled in the art may vary details of construction and arrangements of parts without departing from the spirit of this invention, and therefore it is not desired to be limited to the exact foregoing description except as may be necessary by the claims.

What is claimed is:

1. In a bottle capping machine the combination of means to move a bottle into capping position; means to deliver a bottle cap from a supply of caps to a position for application to a bottle, said delivery means including a member fastened for engagement with a latch; a latch engageable with said member to hold the same against operable movement; a reciprocable capping device for applying the delivered cap to a positioned bottle; and means controlled by the capping movement of said device for disengaging said latch and said member, said means including a member given bodily movement axially of said device, said member operable only when a bottle is in the capping position.

2. In a bottle capping machine the combination of means to move a bottle into capping position; means including a swingable arm to deliver a bottle cap from a supply of caps to a position for application to a bottle; a latch to prevent swinging movement of said arm; a recipro-

cable capping device for applying the delivered cap to a positioned bottle; and means for releasing said latch, said means operable only when a bottle is in the capping position, said releasing means including a member having bodily movement within and axially of said device and actuated by the capping movement of said device.

3. In a bottle capping machine the combination of means to move a bottle into capping position; a swingable arm to move a bottle cap to a position for application to a bottle; a capping device including a plunger for applying the delivered cap to a positioned bottle; and means for rendering the swingable arm operable only when a bottle is in the capping position, said rendering means including a member given bodily movement axially of said plunger by contact of said plunger with the positioned bottle.

4. In a bottle capping machine the combination of means to move a bottle into capping position; a swingable arm to move a bottle cap to a position for application to a bottle; a reciprocable capping device including a plunger for applying the delivered cap to a positioned bottle; and means for rendering the swingable arm operable only when a bottle is in the capping position, said rendering means including a member coaxial with said plunger and given delayed axial movement relative thereto by contact of said plunger with the positioned bottle.

5. In a bottle capping machine the combination of means to move a bottle into capping position; a swingable arm to move a bottle cap to a position for application to a bottle; a reciprocable capping device including a plunger for applying the delivered cap to a positioned bottle; and means for rendering the swingable arm operable only when a bottle is in the capping position, said rendering means including a reciprocable member coaxial with said plunger and having relative movement with respect to said device, said member carried by said device and given relative longitudinal reciprocation by contact of said plunger with the positioned bottle.

6. In a bottle capping machine the combination of means to move a bottle into capping position; latchable means to deliver a bottle cap from a supply of caps to a position for application to a bottle; a capping device for securing the delivered cap to a positioned bottle, said device comprising a casing having a cap portion telescopically connected therewith, the casing having an opening in the end adapted to receive the open end of a bottle having a cap loosely mounted thereon, said casing further provided with a relatively yieldable plunger for holding the loosely mounted cap against the end of the bottle during the securing of the cap on the bottle, said casing and its cap portion being adapted to be moved longitudinally of the bottle, said casing having pivoted levers therein adapted to press the skirt of the cap into secured position upon the bottle, the cap portion of the casing carrying means for operating said levers when said cap portion is forced toward the bottle, and the cap portion of the casing carrying a member yieldably connected with and actuated by said plunger; and means for rendering the cap delivering means operable only when a bottle is in the capping position, said rendering means including a latch and latch operating devices disposed between said latch and said member, said latch operating devices actuated by said member.

7. In a bottle capping machine the combina-

tion of a plate; a cap magazine vertically reciprocable above said plate; spring pressed pivoted dogs carried by said magazine, each dog having a toe movable through the wall of said magazine and adapted to support the stack of caps in the magazine by engagement under the edge of the lowermost cap in the stack; a cam member carried by said plate and adapted to move each dog against the tension of its spring as said magazine nears the end of its downward travel, the toe of each dog being withdrawn from the magazine by such movement to permit the stack of caps to drop upon said plate, each dog having reverse movement as said magazine starts its upward travel to bring the toe of the dog inwardly of the magazine into position under the edge of the next to lowermost cap in the stack, whereby upon continued upward travel of the magazine the lowermost cap will be left deposited upon the plate and the remainder of the caps in the stack will travel with the magazine; a capper reciprocable with said magazine; and means operable over said plate to move the deposited cap to a position beneath said capper.

8. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means to deposit upon said plate the lowermost cap in the magazine as the magazine is completing its downward movement, and to retain in the magazine all of the caps thereabove as the magazine moves upwardly; and means to slide the deposited cap to a position on said platen beneath said capper when said plate and platen are in planar registry.

9. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means operable through the plane of said plate to deposit upon said plate the lowermost cap in the magazine as the magazine is completing its downward movement, and to retain in the magazine all of the caps thereabove as the magazine moves upwardly; and means to slide the deposited cap to a position on said platen beneath said capper when said plate and platen are in planar registry.

10. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means including members disposed above and below the upper surface of said plate to deposit upon said plate the lowermost cap in the magazine as the magazine is completing its downward movement, and to retain in the magazine all of the caps thereabove as the magazine moves upwardly; and means to slide the deposited cap to a position on said platen beneath said capper when said plate and platen are in planar registry.

11. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means including two coating members, one member carried by the magazine and the other member disposed beneath said plate, to deposit upon said plate the lowermost cap in the magazine as the magazine is completing its downward movement, and to retain in the magazine all of the caps thereabove as the magazine moves upwardly; and means to slide the deposited cap to a position on said platen beneath said capper when said plate and platen are in planar registry.
12. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means to deposit upon said plate the lowermost cap in the magazine as the magazine is completing its downward movement, and to retain in the magazine all of the caps thereabove as the magazine moves upwardly; means to slide the deposited cap to a position on said platen beneath said capper when said plate and platen are in planar registry; and means to render said cap sliding means inoperative when said platen has a cap thereon.
13. In a bottle capping machine the combination of a vertically reciprocable carrier consisting of a cap magazine and a capper joined thereto; a stationary plate disposed below the magazine; a platen disposed below the capper, said platen being in the plane of said plate when the carrier is in its upper positions but adapted to move vertically with the carrier when the latter is in its lower positions; means to deposit upon said plate the lowermost cap in the magazine as the magazine is completing its downward movement, and to retain in the magazine all of the caps thereabove as the magazine moves upwardly; latchable means to slide the deposited cap to a position on said platen beneath said capper when said plate and platen are in planar registry; and means controlled by movement of said capper and including a latch engageable with said cap sliding means for releasing the cap sliding means only after the previous platen-carried cap has been applied to a bottle.
14. In a bottle capping machine the combination of a carrier comprising a magazine for a supply of caps and a capper joined to said magazine for movement therewith; means to feed a bottle to a position beneath the capper for application of a cap thereto; means to feed a cap from the magazine to a position between the capper and a bottle to be capped; and means to control the movements of said carrier, said cap feeding means, and said bottle feeding means, said control means comprising a single actuating member mounted upon an operating shaft, and cooperating connections between said member and the respective means to be controlled.
15. In a bottle capping machine the combination of a carrier comprising a reciprocable magazine adapted to deposit at one limit of its move-

ment a cap from a supply of caps, and a capper joined to said magazine for movement therewith; means to feed a bottle to a position beneath the capper for application of a cap thereto; means to feed a cap from its deposited position to a position between the capper and a bottle to be capped; and means to control the movements of said carrier, said cap feeding means, and said bottle feeding means, said control means comprising a single actuating drum-cam mounted upon an operating shaft, and cooperating connections between said drum-cam and the respective means to be controlled.

16. In a bottle capping machine the combination of a carrier comprising a magazine for a supply of caps and a capper joined to said magazine for movement therewith; means to feed a bottle to a position beneath the capper for application of a cap thereto; means to feed a cap from the magazine to a position between the capper and a bottle to be capped; and means to control the movements of said carrier, said cap feeding means, and said bottle feeding means, said control means comprising a single rotating drum having two cam grooves formed therein cooperatively receiving members for actuating the respective means to be controlled.

17. In a bottle capping machine the combination of a carrier comprising a magazine for a supply of caps and a capper joined to said magazine for movement therewith; means to feed a bottle to a position beneath the capper for application of a cap thereto; means to feed a cap from the magazine to a position between the capper and a bottle to be capped; and a rotating drum having one cam groove formed in its cylindrical face and a second cam groove formed in one of its flat faces, and actuating members cooperatively associated with said grooves to control the movements of said carrier, said cap feeding means, and said bottle feeding means.

18. In a bottle capping machine the combination of a carrier comprising a magazine for a supply of caps and a capper joined to said magazine for movement therewith; means to feed a bottle to a position beneath the capper for application of a cap thereto; means to feed a cap from the magazine to a position between the capper and a bottle to be capped; a rotating drum having one cam groove formed in one of its flat faces, and having a second cam groove formed in its cylindrical face; and actuating members cooperatively associated with said grooves to control the movements of said carrier and said cap feeding means through the formation of one of said grooves, and to control the movement of said bottle feeding means through the formation of the other of said grooves.

19. In a bottle capping machine the combination of means to feed a bottle to capping position; a magazine for a supply of caps including means to feed a cap from the magazine to a position above a bottle to be capped; a capper for applying the positioned cap to the bottle, said capper comprising a casing and a cap portion telescopically associated therewith, said casing and its cap portion adapted to be reciprocated, said casing open at its bottom to receive the top of an open bottle and the cap to be applied thereto upon the downward movement of the capper, a plunger within the casing adapted to hold the positioned cap against the top of the bottle while the cap is being secured thereto, a series of pivoted levers within the casing adapted to crimp the edges of the cap about the bottle, a tubular

member carried by the cap portion of the capper and having a cone shaped cam formed thereon for operating the pivoted levers, a tube yieldably supported within the tubular member and having yieldable relation with the end of said plunger, a rod slideable within said tube with a pin and slot connection therebetween adapted to permit a delayed action of said rod when said plunger and

said tube are moved relative to the capper by contact between said plunger and a bottle; and connections between said rod and the cap feeding means whereby a cap is fed to capping position only when a bottle is in the capping position.
